UNITED STATES PATENT OFFICE.

CHARLES HORAN, OF NEW YORK, N. Y.

HEAD-PROTECTOR.

1,875,845.

Specification of Letters Patent. Patented Apr. 26, 1921.

Application filed September 10, 1920. Serial No. 409,320.

To all whom it may concern:

Be it known that I, CHARLES HORAN, a citizen of the United States, residing at New York city, in the county of New York and State of New York, have invented certain new and useful Improvements in Head-Protectors, fully described and represented in the following specification and the accompanying drawing, forming a part of the same.

This invention relates to head protectors. The invention has been made with the idea of providing a head protector for use by baseball batters, lacrosse players, hockey players, etc., and the invention aims to provide a head protector of light weight and of simple design which may be readily put on and off and may be worn with but little discomfort and without interfering with the vision or freedom of the wearer, and which shall afford adequate protection to the vulnerable parts of the wearer's head and neck against impact of a baseball or blows from a lacrosse stick or other game implement.

The use of the device is of course not limited to athletic games or sports, the device being useful wherever protection such as it affords is desirable.

An understanding of the invention can best be given by a description in connection with drawings illustrating an approved embodiment of the invention, and such a description will now be given in connection with the accompanying drawings, in which:—

Figure 1 is a perspective view of a head protector embodying the invention in the form now considered best; and

Fig. 2 is a sectional view of the protector. The protector as shown in the drawings consists of a slab of light, resilient and slightly flexible shock-absorbing material shaped to extend about the back of the head and neck of the wearer and forward about the sides of the head sufficiently far to protect the temples and most desirably entirely open in front to leave the face of the wearer uncovered. Most desirably it is of approximately the shape shown, that is of a general U shape in cross-section with the front side portions 10 and 11 extending somewhat inward toward each other and having its rear and side walls extending vertically straight, or it may be described as of hollow cylindrical or approximately cylindrical form open at the front. The

protector is made of sufficient depth to extend from near the top of the head down past the base of the skull, and of suitable size so that its front edge portions will protect the temples, and is best shaped so that its front side portions will lightly grip the sides of the wearer's head. When so shaped, the protector will maintain its position on the head of the wearer through its inherent elasticity, and the provision of additional securing or holding means is unnecessary. Ear openings 12 and 13 are formed in the sides of the protector, which may be recesses extending upward from the bottom edge as shown.

The protector is best formed of a plurality of thin sheets of cork cemented together in the desired shape with a thin layer or filling between the sheets or layers to add to the strength and resiliency of the built up slab. It is important to use a suitable cement, and I have found a casein cement known as "casein compound" most suitable, and for a filler I use a small quantity of comminuted bamboo and a small quantity of comminuted rubber. Bamboo is used because of the strength and elasticity of its fiber, and the rubber aids in securing the desired limited degree of flexibility combined with high resiliency.

In making a protector, the several sheets or layers of cork of suitable size are most conveniently laid together flat with the cement and filler between the cork sheets, a cork sheet being placed on a flat support, its surface being then covered with the casein cement and a small amount of the comminuted filling material, when used, being evenly distributed over the cement covered surface. The next layer of cork is then applied and coated, and another layer of cork applied, and so on until the desired number of sheets have been laid together. Then before the cement sets the built up slab is placed about and pressed together against a form, most desirably under high pressure, whereby all the layers are pressed together into close contact, and is so held until the cement has set. The edges of the protector are then finished off and the portions adjacent the front edges are tapered off preferably on the inner side as shown, and the ear openings are cut out unless such openings were formed in the sheets before being laid together to form the slab.

I have found that a protector made as

described of five sheets or layers of cork each a little less than one-eighth of an inch in thickness, with the layers secured together by casein compound and with a filling between the layers comprising in the whole protector a total of about 1 oz. of comminuted bamboo and about 1½ ozs. of comminuted rubber, has the strength and resiliency, resistance to impact, and shock-absorbing quality necessary for affording adequate protection against missiles such as baseballs and against blows such as might be expected to be received in playing lacrosse and similar games. The comminuted bamboo used is preferably of about the degree of fineness of coarse sawdust and the comminuted rubber is somewhat finer.

What is claimed is:

1. A head protector formed of a slab of light, resilient and slightly flexible shock-absorbing material shaped to extend about the back of the head and neck of the wearer and forward about the sides of the head sufficiently to protect the temples and being open in front and adapted to lightly grip the sides of the head through its inherent elasticity and thereby retain its position.
2. A head protector formed of a slab of light, resilient and slightly flexible shock-absorbing material shaped to extend about the back of the head and neck of the wearer and forward about the sides of the head sufficiently to protect the temples and being open in front and having an ear opening on each side and being adapted to lightly grip the sides of the head through its inherent elasticity and thereby retain its position.
3. A head protector formed of a slab of light, resilient and slightly flexible shock-absorbing material composed principally of cork shaped to extend about the back of the head and neck of the wearer and forward about the sides of the head sufficiently to protect the temples and being open in front and adapted to lightly grip the sides of the head through its inherent elasticity and thereby retain its position.
4. A head protector formed of a plurality of thin sheets of cork cemented together and shaped to extend about the back of the head and neck of the wearer and forward about the sides of the head sufficiently to protect the temples and being open in front and adapted to lightly grip the sides of the head

through its inherent elasticity and thereby retain its position.

5. A head protector comprising a substantially cylindrical slab open at the front and adapted to extend approximately around the head of the wearer and consisting of a plurality of thin sheets of cork cemented together.

6. A head protector formed of resilient shock absorbing material composed of a plurality of thin sheets of cork cemented together and shaped to extend about the head of the wearer.

7. A head protector comprising a substantially cylindrical slab open at the front and adapted to extend approximately around the head of the wearer and consisting of a plurality of thin sheets of cork cemented together with a layer of finely divided filler between some of the adjacent sheets.

8. A head protector comprising a substantially cylindrical slab open at the front and adapted to extend approximately around the head of the wearer and consisting of a plurality of thin sheets of cork cemented together with comminuted bamboo distributed between the cemented sheets.

9. A head protector comprising a substantially cylindrical slab open at the front and adapted to extend approximately around the head of the wearer and consisting of a plurality of thin sheets of cork cemented together with comminuted rubber distributed between the cemented sheets.

10. A head protector comprising a substantially cylindrical slab open at the front and adapted to extend approximately around the head of the wearer and consisting of a plurality of thin sheets of cork having between the sheets a thin layer of comminuted bamboo, comminuted rubber and casein cement, the cement serving to secure the sheets and filler together to form a resilient and slightly flexible slab.

11. A head protector of hollow approximately cylindrical form open at the front and formed of a plurality of thin sheets of cork cemented together with casein cement.

In testimony whereof I have hereunto set my hand in the presence of two subscribing witnesses.

CHARLES HORAN.
